UNITED STATES PATENT OFFICE

161,750

WREN HOUSE

Emil R. Hahn and Louise Baerman,
Fort Atkinson, Wis.

Application December 11, 1946, Serial No. 135,414

Term of patent 7 years

(Cl. D31—2)

To all whom it may concern:

Be it known that we, Emil R. Hahn and Louise Baerman, citizens of the United States of America, residing at Fort Atkinson, in the county of Jefferson and State of Wisconsin, respectively, have invented a new, original, and ornamental Design for a Wren House, of which the following is a specification, reference being had to the accompanying drawing, forming a part thereof wherein:

Figure 1 is a side view of a wren house, showing our new design.

Figure 2 is a top plan view.

Figure 3 is a front view.

Figure 4 is a rear view.

We claim:

The ornamental design for a wren house, as shown.

EMIL R. HAHN.
LOUISE BAERMAN.
